AUDIO FREQUENCY TRANSFORMER

Donald O. Schwennesen, Skokie, Ill., assignor to Chicago Standard Transformer Corp.

Application December 21, 1953, Serial No. 399,551

1 Claim. (Cl. 336—183)

This invention relates to an audio frequency transformer primarily adapted for use in plate circuit modulation of an appropriate radio frequency carrier. The transformer primary is adapted to be energized from push pull amplifying means, while the secondary is adapted to be connected in the plate circuit of a modulating stage for the purpose of modulating a suitable radio frequency carrier. In addition, the invention is applicable to other transformers such as output transformers.

It is well known that capacitance between the windings of an audio transformer and between the windings and ground affects the operation of the transformer. Parasitic series and parallel resonant circuits are developed and the transformer characteristic is modified as a result. One solution to the problem has been provided in a previous invention by the present inventor described in Patent No. 2,430,738. In that case, sub-divided windings were used and the windings so connected electrically that capacitive effects were concentrated and easily compensated for. The sub-divided windings, however, introduced obvious winding difficulties. The present invention provides a means of connecting standard, as opposed to sub-divided, windings as an improvement over the previous invention. In addition, the leakage inductance is decreased improving the high frequency characteristic.

The drawing illustrates a transformer wound in accordance with the teachings of this invention. A shell type transformer construction is illustrated, however, the invention is equally applicable to the core type.

The shell type transformer is indicated generally at 10. Laminations 11 and 12 are joined and mated in accordance with customary practice. In addition, the windings are assembled on the core in accordance with well known practice.

The windings, as hereinbefore stated, are all full length windings and are annularly disposed about the central lamination leg 13. Windings 14, 16, 19, and 21 are the primary windings. All primary windings are wound in the same direction. The direction of windings is indicated by the circle located in the center of each winding. A dot located in the circle indicates winding in one direction and a cross indicates an oppositely wound winding.

The secondary windings are indicated at 15, 17, 18, and 20. Secondary windings 15 and 17 are wound in the same direction as the primary windings. Secondary windings 18 and 20 are wound in the opposite direction.

It is to be understood that the primary and secondary windings are separated by suitable insulation 22.

With respect to the windings, it is preferable that primary windings have the same number of turns although the number of turns may vary in accordance with the characteristic desired.

The windings are provided with terminals hereinafter referred to as inner and outer terminals. The terms "inner" and "outer" relate the position of the winding ter-

2

rninal to the central leg 13. The inner terminal is always at the beginning of the winding while the outer terminal is always at the end of that particular winding.

The primary winding includes the lead wires 23 and 24 and a lead 25 from the center tap which is joined to a source of B+ potential. The secondary winding includes the lead 26 from a source of B+ potential and the output lead 27.

The primary windings are in series relationship. A current path can be traced from the lead 23 to inner terminal 28, primary winding 14 to outer terminal 29. From outer terminal 29 to inner terminal 38, primary winding 19 and outer terminal 39. Thence to inner terminal 32, primary winding 16 and outer terminal 33. Thence to inner terminal 42, primary winding 21, outer terminal 43 to input lead 24. Thus, the primary windings 14, 19, 16, and 21 are in series respectively.

In the secondary circuit, two parallel circuits are connected in series. Each parallel circuit includes two secondary windings oppositely wound. The lead 26 is connected in parallel to inner terminal 36 and outer terminal 41 of windings 15 and 20. Windings 15 and 20 are, therefore, in parallel. Outer terminal 31 and inner terminal 40 are joined to a common lead which connects inner terminal 34 and outer terminal 37 in parallel. Windings 17 and 18 are therefore in parallel. Outer terminal 35 and inner terminal 36 are joined in the common lead 27 which is the output lead. Thus, it can be seen that the oppositely wound windings 15 and 20 are connected in parallel with each other and in series with the parallel connection of windings 17 and 18. As previously indicated, each pair of windings in parallel includes one winding wound in one direction and one winding wound in the other direction.

As a result of connecting the windings in this manner, distributive capacitive effects are concentrated. The parasitic resonant effects are concentrated into two parasitic circuits so that the effects may be compensated for. The capacitance between primary 21 and secondary 20, and between primary 14 and secondary 15 is concentrated. Similarly, the capacitance between secondary 20 and primary 19, between secondary 15 and primary 16, as well as the capacitance between primary 19 and secondary 18, and primary 16 and secondary 17 is concentrated and as before compensation can be had in any desired manner.

Having described my invention, I claim:

A transformer consisting of full length primary and secondary windings annularly disposed the one upon the other in the following manner, an innermost first primary, a second secondary, a third primary, a fourth secondary, a fifth reversely wound secondary, a sixth primary, a seventh reversely wound secondary, and an eighth primary, all of said windings having inner and outer terminals respectively and connected as follows; the first, second, third and eighth primary windings are connected in series with the outer terminals of an inner winding connected to the inner terminal of an outer winding, the second and seventh secondary windings connected in parallel to each other and in series with the parallel connection of the fourth and fifth secondary windings.
